UNITED STATES PATENT OFFICE.

JOSEPH V. ROBINSON, OF BRANFORD, CONNECTICUT.

AUTOMATIC TRAIN-PIPE COUPLING.

1,245,778.

Specification of Letters Patent.

Patented Nov. 6, 1917.

Application filed December 19, 1912, Serial No. 737,728. Renewed September 13, 1917. Serial No. 191,305.

To all whom it may concern:

Be it known that I, JOSEPH V. ROBINSON, a citizen of the United States, and resident of Branford, in the county of New Haven, 5 State of Conn., have invented certain new and useful Improvements in Automatic Train-Pipe Couplings, of which the following is a specification.

This invention relates to improvements in 10 automatic train pipe couplers for railway cars and has for its object to produce an improved train pipe coupler of the pin and funnel construction provided with an improved support for the coupling head which 15 permits free universal movement thereof, whereby in coupling the heads are accurately alined with socket portions of their guiding members in advance of seating therein, whereby the last inch or so of movement of the heads in coupling is strictly parallel. With this construction an air tight 20 joint between mating connector faces obtains under all conditions of service, without the use of auxiliary locks or complex parts.

25 The invention consists in the novel combinations, improvements and constructions hereinafter described, pointed out in the appended claims and illustrated in the accompanying drawings, in which:

30 Fig. 1, is a side elevation of a part of a car coupler with one of my improved connectors attached.

Fig. 2, is a front face view of the connector shown in Fig. 1.

35 Fig. 3, is a detail view of the connection between the base of my improved connector and the bracket of the car, and

40 Fig. 4, is a horizontal section of two of the improved couplings connected, showing the construction of their gathering means and socket portion.

Referring to the drawings: The car coupler 10 is provided with a lug 11 to which a bracket 12 is suitably connected, the bracket 45 being offset at 12^a to pass around the lug 11 and form a seat therefor. An abutment 12^b, integral with the bracket, engages the base A between the two halves thereof, and supports the same against longitudinal shifting, serving also to free the bolts 14 of the 50 shearing strains of service; see Figs. 1 and 3. This produces a construction in which a standard form of base A can be efficiently connected with a lug 11 and centrally supported therefrom relative to the car coupler, regardless of the position of the lug on the

coupler; that is the depth, or width, of the seat portion of the offset 12^a which extends beneath the lug 11 will be such that when the bracket is secured in position the base carried thereby will be properly located with reference to the coupler.

The said base A comprises two halves 13, each of which is provided with an overhanging portion 16 that conforms to the contour 65 of the base coil of the buffer spring 17, around which they are securely clamped by the bolts 14 and 15. The said spring 17 consists of a series of coils of gradually decreasing diameter, coiled preferably of a 70 flat bar having a common thickness and a tapering width, whereby the metal of the several coils is thinner radially than axially. The small end of the spring supports, extended away from the base A, a coupling 75 head B of the pin and funnel type, in which a funnel 18 is provided with a cylindrical portion 19 adapted to snugly receive a correspondingly shaped portion 20 of a forwardly extending guiding pin or prong 21 80 of an opposing coupling.

This arrangement comprehends a highly advantageous construction in which a pin and funnel coupling head is supported for free universal movement from the normal 85 position by a spring which imparts to the head a varying resistance increasing in greater progression than the extent of such movement; the resistance to longitudinal movement of the head, by virtue of the conformation of the spring coils, being greater, and to lateral movement less, proportionately, than that offered by a spring of different construction. In this manner the minimum resistance is presented to lateral shifting of coupled heads, greatly reducing the strains thereupon that tend strongly to separate the heads, caused by the sharp whipping movements of running cars. This free universal support of the head allows the 90 latter to yield readily to the guiding action of the pin and funnel throughout their entire range of movement in coupling, insuring that the relative movement between the cylindrical portions 19 and 20 of engaging 95 100 couplers will be strictly parallel under all conditions of service, thereby obtaining a close fit between these members, constituting a positive interlocked connection, which will prevent leaks and "opening up" of the coupling heads in running; see especially Fig. 4.

In those constructions where the coupling

head B is held against downward movement at moment of initial engagement, this interlock cannot be obtained, for in such designs when one car is higher than another, the extremity of the guiding pin 21 enters the apex of the funnel 18 at an angle to the longitudinal axis thereof, necessitating that the opening in the apex be larger than the said extremity, thus destroying all possibility of a firm interlock therebetween, and rendering parallel movement of the guiding prongs 21 relative to the apex of the funnels 18 impossible, in coupling on uneven tracks. The present construction is free from these objections, allowing free universal movement of the coupling head from the normal position, as stated, and permitting of such movement without axial compression of the spring 17.

Any suitable conduit for directing a fluid to the coupling head B may be used with my improved support. For this purpose I show a conduit or pipe 22 having an enlarged end 23 extending through the coupling head and carrying an oscillating gasket 24 of suitable material, preferably non-yielding. In coupling the gasket mates with a correspondingly shaped gasket in a counterpart head, and to insure against possible leakage, I provide the gasket with an auxiliary gasket or sealing member 25 and mount it in an undercut seat 26 in the first mentioned gasket. A retaining ring 27 of suitable construction retains the gasket in the pipe 22.

To prevent undue rotary movement of the coupling head B, I provide the pipe with a flattened or oblong portion 28 which extends through an oblong opening 29 in the base A and fits closely therein. To prevent undue movement of the coupling head forwardly of the base, I mount on the rear end of the pipe 22 a suitable elbow 30 for receiving the train pipe hose 31, and provided with a shoulder 32 for abutting the rear face of the base A to prevent, as aforesaid, undue forward movement of the coupling head B.

Thus I provide a simple and efficient support for a pin and funnel coupling head which will permit universal movement and automatic interlocking thereof without jamming or binding strains and maintain an efficient air tight connection under all conditions of service.

Having thus described my invention, what I claim as new and desire to secure by United States Letters Patent is:

1. The combination with a railway car draft coupler having a depending lug, of a supporting bracket comprising two substantially vertical sections connected by an intermediate offset adapted to receive said lug, the upper section being secured against a side face of the lug, and a train pipe connector base having a bifurcated upper end

which receives the lower end of said bracket, and is secured thereto, substantially as and for the purpose described.

2. The combination with a railway car draft coupler having a depending bracket, of a train pipe connector base bolted to the bracket, and means on the bracket, below the connection thereof with the base, engaging said base and acting to relieve the connecting bolts from shearing strain when the connector is in use.

3. The combination with a railway car draft coupler having a depending bracket, of a two part train pipe connector base having its members extending on opposite sides of and bolted to the bracket, and an abutment 12^b on the bracket bearing against the rear faces of both members of said base, for the purpose described.

4. In an automatic train pipe coupling, the combination of a coupling head provided with a gasket, and a spring for extending said head and for resisting longitudinal movement thereof with a greater force than it imparts to lateral movement of said head, said spring consisting of a series of coils of metal thinner radially than axially and having one end seated substantially in the plane of the coupling face of said head.

5. In an automatic train pipe coupling, the combination of a coupling head, and a spring for extending said head and for resisting movement thereof with a varying force increasing in greater progression than the extent of such movement, said spring consisting of a series of coils of metal thinner radially than axially and varying in axial thickness.

6. In an automatic train pipe coupling, the combination of a coupling head, and a spring for extending said head and for placing the head under pressure, said spring consisting of a series of coils of metal thinner radially than axially and varying in axial thickness.

7. In an automatic train pipe coupling, the combination of a supporting base, a coupling head, and a spiral spring for extending the head interposed between said head and base and having its rear end seated on the base, the metal of the coils of said spring being thinner radially than axially and tapering in axial thickness from the rear to the front end of the spring.

8. In an automatic train pipe coupling, the combination of a coupling head, a spring consisting of a series of coils rectangular in cross section maintained in supporting relation to said head, a two-piece base provided with a socket for closely receiving the base coils of said spring, and means for clamping the two pieces of said base together to lock said spring in said socket.

9. In an automatic train pipe coupling, the combination with a base having a central

opening for a fluid pipe and a seat surrounding said opening and having walls adapted to embrace the end of a spring, of a tapering coiled spring having its larger end seated in said seat, a fluid pipe engaging the small end only of said spring whereby the pipe is sustained yieldingly in a horizontal position by the spring, and pin and funnel

guiding means mounted on the outer end of said pipe. 10

In testimony whereof I affix my signature in presence of two witnesses.

JOSEPH V. ROBINSON.
